His Attorney

UNITED STATES PATENT OFFICE.

EDGAR F. COLLINS, OF SCHENECTADY, NEW YORK, ASSIGNOR TO GENERAL ELECTRIC COMPANY, A CORPORATION OF NEW YORK.

ELECTRIC FURNACE.

1,271,280.

Specification of Letters Patent.

Patented July 2, 1918.

Application filed May 12, 1917. Serial No. 168,270.

To all whom it may concern:

Be it known that I, EDGAR F. COLLINS, a citizen of the United States, residing at Schenectady, county of Schenectady, State of New York, have invented certain new and useful Improvements in Electric Furnaces, of which the following is a specification.

The present invention comprises an electrode arrangement suitable for furnaces in which industrial operations are carried out, such as the melting of metals and the heating of steel for forging, annealing, tempering and the like. In furnaces of this nature it is desirable that the electrodes should be of rugged construction, easily replaceable and readily adjustable for the purpose of regulating the operation of the furnace.

It is the object of my invention to provide a furnace in which the electrode which is subject to deterioration and wearing away by the action of an arc can be readily replaced with a minimum of cost and interruption of service. With this object in view, I have provided a furnace containing an electrical conductor or conductors built into the container of the furnace in fixed relation, and a replaceable conductor of such configuration that it can be readily placed to make good electrical contact with the conductor and when burned away can be easily readjusted or replaced to continue the operation of the furnace.

In the preferred embodiment of my invention, I have provided electrical conductors with diverging sides in contact with which are located movable blocks conforming in surface configuration with the opposing surface of the fixed conductors. The novel features of my invention will be explained with greater particularity in the following description taken in connection with the accompanying drawing, and as pointed out in the appended claims.

Figure 1 is a perspective view of furnace electrodes which are constructed in accordance with my invention, part of the container being broken away to show the relation of the electrodes, and Fig. 2 is a fragmentary sectional view of the furnace.

Referring to the drawing, the furnace comprises a container 1 consisting of firebrick, or other suitable refractory material reinforced by steel plates 2. As shown in Fig. 1, the material to be heated is contained

within a hearth or crucible constituted by 55 the base 3 of the container and upwardly extending wall 4, consisting of carborundum brick or other suitable heat-conductive refractory material. Located closely adjacent to the wall 4 are substantially parallel, 60 prismatic rods 6 consisting of carbon, graphite or the like, the opposing faces of which diverge upwardly. Coöperating with the conductor constituted by the rods 5, 6, are replaceable blocks 7, 8, having a surface 65 configuration adapting them to fit snugly within the recess between the sides of the rods 5, 6. In the particular form illustrated, the blocks 7, 8 have a hexagonal cross section so that when one of the blocks becomes 70 hollowed out otherwise worn by the action of the arc the block may be reversed, or if necessary replaced, and the operation of the furnace continued. Coöperating with these blocks are movable electrodes, 9, 10, projecting through the roof of the furnace and adapted to maintain an arc between their ends and the arc blocks. As shown in Fig. 2 the arc is preferably surrounded by conductive granular material 11, such as coke or 80 other suitable form of carbon. It is to be understood that the replaceable blocks 7, 8 may be given any other desired surface configuration which will enable them to make good electrical contact with the fixed conductors within the furnace. 85

It has been found that this construction is particularly useful in electric furnaces used for the melting of metals, such as brass, which after melting may be discharged 90 through the spout 12. The metal during the heating operation is protected from direct heat radiation of the arc by the wall 4 but receives heat by conduction and by reflection from the walls of the furnace. Another set 95 of electrodes 13, 14, may be provided on the opposite side of the hearth. Structural features of the furnace itself are not part of my invention but are described and claimed in a Patent No. 1,242,275, issued Oct. 9, 100 1917, by Irving R. Valentine.

What I claim as new and desire to secure by Letters Patent of the United States, is,

1. An electric arc furnace comprising paired electrical conductors located adjacent each other, one or more replaceable electric conductors conforming in surface configuration with said paired conductors to make 105

- contact therewith and a movable electrode coöperating with said replaceable conductor or conductors.
2. An electric furnace comprising a container, electrical conductors located adjacent each other on the base of said container, replaceable conductive blocks electrically in contact with said conductors and electrodes projecting through said container in arcing relation with said blocks.
3. An electric furnace comprising prismatic conductors located adjacent each other on the base of said furnace and having upwardly diverging sides, a replaceable conductive block conforming in surface configuration with said conductors to make intimate contact therewith and an adjustable electrode coöperating with said block to support an electric arc.
4. An electric arc furnace comprising an electrical conductor providing a recess, a replaceable conductive block fitted to said recess and electrically in contact with said conductor, and an electrode projecting in arcing relation to said block.

In witness whereof, I have hereunto set my hand this 11th day of May, 1917.

EDGAR F. COLLINS.
